UNITED STATES PATENT OFFICE.

BENJAMIN WHITTAKER, OF NEW YORK, N. Y.

PIPE-WRENCH.

No. 880,612.

Specification of Letters Patent.

Patented March 3, 1908.

Application filed January 19, 1907, Serial No. 353,052. Renewed January 17, 1908. Serial No. 411,326.

To all whom it may concern:

Be it known that I, BENJAMIN WHITTAKER, a citizen of the United States, residing at New York, in the county of New York and State of New York, have invented certain new and useful Improvements in Pipe-Wrenches, of which the following is a specification, reference being had therein to the accompanying drawing.

10 This invention relates to pipe wrenches in which a chain is employed in connection with a serrated head to grip the pipe.

The invention is adapted to wrenches hitherto devised and in use, and is also embodied in new constructive details as herein-after set forth.

15 The invention consists in the combination with a wrench of the class referred to in which serrated and bifurcated jaws form the fixed head of the wrench and between the bifurcated jaws a chain is passed that embraces the pipe, of a gripping block that may be secured between the jaws or rendered adjustable therewith to adapt the wrench for 20 use upon beaded or flanged pipe fittings.

25 In the accompanying drawing, forming a part of this specification, a wrench is illustrated of the type referred to and with which the present invention is incorporated.

30 In the several figures the same numerals of reference indicate corresponding parts.

Figure 1 is a side elevation partly in section. Fig. 2 a face or front view. Fig. 3 an end view of Fig. 1. Fig. 4 a side view of the 35 serrated head and removable block rendered adjustable therewith. Fig. 5 a similar view showing another means of adjusting the block. Fig. 6 an end view of Fig. 5; and Figs. 7 and 8 views of the block detached as 40 designed for use, respectively, with the construction shown in Figs. 7 and 8.

45 As shown in Fig. 1, 9 represents the handle or bar; 10 the serrated jaws forming the head and fixed upon opposite sides of the bar 9; 11 is the chain pivoted to the bar and arranged to embrace the pipe or coupling 12 and passed between the jaws of the head with its free end connected with the bar in the usual way. In this figure, the wrench is 50 shown as applied to a section of a beaded coupling, the bead or flange of the coupling being represented at 13 in dotted line.

55 14 is a block or auxiliary jaw which is arranged between the bifurcated and fixed jaws of the wrench and is also provided with a similar serrated face. This block 14 is

made separate and adapted to be applied to wrenches of the type shown hitherto devised and in use and is also adapted for adjustment relative with the serrated face of the fixed head of the wrench to form a gripping surface flush with the gripping surface of the head or depressed to grip the bead or flange of a coupling coincident with the gripping surface of the head as shown in Fig. 1. 60 Any suitable means may be used for securing the block within the jaws of the wrench and any suitable devices may also be employed to adjust the block relatively with the fixed jaws without departing from the spirit of the 65 invention.

In the present instance, different means are shown for adjusting the block, Fig. 4 showing the block adapted to slide in a guide way 15 in one of the jaws and provided with 70 a slot 16 that engages a stud and nut 17 by which it is secured at a desired point.

In Fig. 5 an alternative means of adjusting the block is shown consisting in a threaded stem 18 extending from the end of the 75 handle bar 9 and in line therewith, whereby a vertical adjustment of the block effects the same relative position of it with the operating face of the head. This adjustment is effected by turning the stem 18 by means of 80 the slot at its end as shown at 19, Fig. 6, which causes the block 14 to move up or down and vary the distance of its serrated face with respect to the serrated face of the head. 90

In the construction of the block 14 and its attachment to the wrench, I wish it understood that the block may be secured in place by any suitable means and with or without an adjusting device as I do not wish to confine or limit the invention to such details of construction. 95

What I claim and desire to secure by Letters-Patent is:—

1. A wrench comprising in combination, 100 an operating handle, a bifurcated holding head having serrated jaws, a connected clamping chain coöperating with said head to grip a pipe or other article, and a separable gripping block interposed between the 105 jaws adapted to engage with a beaded or projecting portion of the pipe or pipe fittings, or other article.

2. A wrench comprising in combination, 110 an operating handle, a bifurcated holding head having serrated jaws, a connected clamping chain coöperating with said head

2
to grip a pipe or other article, a gripping block interposed between the jaws adapted to engage with a beaded or projecting portion of the pipe or pipe fittings, or other article, 5 and means for adjusting said block relatively with the gripping surface of the holding head.

In testimony whereof I affix my signature in presence of two witnesses.

BENJAMIN WHITTAKER.
